UNITED STATES PATENT OFFICE.

FREDERIC S. THORNLEY, OF PIERRE, SOUTH DAKOTA, ASSIGNOR OF
ONE-HALF TO W. S. LITTLE, OF PIERRE, SOUTH DAKOTA.

VOTING-MACHINE.

No. 832,932.

Specification of Letters Patent.

Patented Oct. 9, 1906.

Application filed May 8, 1905. Serial No. 259,476.

To all whom it may concern:

Be it known that I, FREDERIC S. THORNLEY, a citizen of the United States of America, and a resident of Pierre, Hughes county, South Dakota, have invented a new and useful Voting-Machine, of which the following is a specification.

The object of this invention is to provide improved means for indicating and recording the will and choice of an elector.

A further object of this invention is to provide means to enable an elector to select individuals from groups of candidates and indicate and record his choice among various candidates on various tickets.

A further object of this invention is to provide means whereby a straight ticket may be voted, means for locking the machine against the voting of any other straight ticket, means for scratching the straight ticket voted and voting for corresponding offices in either of the other tickets, means for canceling the straight ticket voted and voting any other straight ticket, means for scratching the subsequent straight ticket and voting for corresponding offices on any other ticket, means for canceling the entire vote, means for canceling and rendering unvotable any office for which an elector is not entitled to vote, means for canceling a mechanical vote for any office and supplying a ballot for such office, means for receiving such ballot by the machine, means for locking the mechanical voting devices on the selection of a ballot by the elector, and means independent of all other voting means for voting "Yes" or "No" on a question.

Further objects of this invention will appear throughout the specific description of the means employed and the method of operation thereof, hereinafter more fully set forth.

My invention consists in the construction, arrangement, and combination of elements hereinafter set forth, pointed out in my claims, and illustrated by the accompanying drawings, in which—

Figure 1 is a front elevation of the machine, partly in section. Fig. 2 is a rear elevation of the machine, the rear closing-plate or door being removed. Fig. 3 is a horizontal section of the machine on the indicated line 3 3 of Fig. 1. Fig. 4 is an elevation of

locking devices for individual or single candidate offices. Fig. 5 is an elevation of locking devices for group or plural candidate offices. Figs. 6, 7, 8, and 9 are detail views of parts of the mechanism employed. Fig. 10 is a plan illustrating the booth and lever connections whereby the entrance of electors to and exit from the face of the machine are controlled and the vote is registered.

In the main views of the drawings the machine is shown in position and with its parts arranged for the entrance of an elector to a voting booth or inclosure and prior to any act of voting by said elector, except that in Fig. 1, for convenience, the uppermost mechanical ticket is shown in "voted" position.

In a general way the machine is constructed of a casing adapted to contain and support various operating devices, and said casing comprises a bottom plate 10, end plates 11 12, a back plate 13, a top plate 14, and vertical partition-plates 15 16, parallel with the back plate.

A plurality of straight-ticket keys 17 are provided, one key for each mechanically-voted ticket on the machine, and said keys are arranged in a vertical row near the end plate 11 of the casing and are journaled by means of shafts or arbors 18, mounted for oscillation in the partition-plate 16. The keys 17 normally lie parallel with each other in approximately horizontal planes, and in the operation of indicating a vote, as hereinafter set forth, said keys are moved (one at a time) into vertical planes against the resilience of springs 17^a on the plate 16, impinging said keys. Arms 19 are mounted rigidly on and extend obliquely downward from the shafts or arbors 18 and move through arcs in the oscillation of said shafts.

A plurality of candidate-keys 20 are provided, one key for each candidate to be voted for on the machine, and said keys are arranged in horizontal rows throughout each of the tickets in the planes of the straight-ticket keys 17 and also are arranged in vertical rows in respect of the offices to be filled by the respective candidates. The keys 20 are journaled by means of shafts or arbors 21, mounted for oscillation in the partition-plate 16, and said keys extend approximately horizontally toward the straight-ticket keys 17 normally. Arms 22 are mounted rigidly on

and extend obliquely downward from the shafts or arbors 21 and move through arcs in the oscillation of said shafts.

Referring to Fig. 6, it will be observed that 5 a shoulder 23 is formed on or fixed to each of the arbors 21, and a spring 24 is mounted between and impinges said shoulder and the partition-plate 16. It is the function of the springs 24 to hold the keys 20 and their arbors in whatever position they may be placed manually. Straight-ticket bars 25, one for 10 each mechanically-voted ticket, are mounted parallel with each other in horizontal planes and are arranged for reciprocation in slide-bearings 26, fixed to the front face of the partition-plate 16. Each of the bars 25 is arranged immediately below a ticket row of keys. The straight-ticket keys 17 are held 15 against movement above their normal positions by springs mounted on the partition-plate 16 and engaging the arms 19 at times. Studs 27 are mounted in and project horizontally forward from the bars 25 and are adapted to be engaged by the arms 19 at times to move said bars toward the end plate 12. 20 Studs 28 and 29 are formed on or fixed to the bars 25 and project horizontally forward and are adapted to engage the arms 22 and oscillate the arbors 21 and keys 20 in one direction. The studs 28 serve the additional purpose of preventing the movement of the arms 19 beyond the studs 27. The studs 29 serve 25 the additional purpose of engaging opposite faces of adjacent arms 22 and oscillating the arbors 21 and keys 20 in the opposite direction at times, and to this end an extra stud 29 is provided at the extreme right of each ticket row. Stops 30 are mounted in and project horizontally forward from the partition-plate 16 adjacent each key 20 and are 30 adapted to engage and stop the rearward movement of the arms 22, and thereby determine the degree of oscillation of the arbors 21 and keys 20 in one direction. Links 31 are pivotally supported on the partition-plate 16 and extend through slots 32 in said plate. The forward end portions of the links 31 are attached to retractile springs 33, fixed in turn to the plate 16. The links 31 extend 35 across end portions of the bars 25 and serve to move said bars to the left into their normal positions after the bars have been moved to the right by manual force applied to the keys 17. A shaft 34 is mounted for oscillation in a vertical plane adjacent the end plate 11, and a plurality of pawls 35 are mounted on and project in opposite directions from said shaft. The pawls are adapted to extend at times through slots 36 in the 40 plate 16 and engage in slots 37 in the ends of bars 25 and move said bars to the left beyond their normal positions. A torsional spring 38 connects the shaft 34 to the top plate 14 and serves to return said shaft and the bars 45 25 to normal position after they have been

oscillated. A crank-arm 39 on one end portion of the shaft 34 is connected by a rod 40 to a turnstile 41 in and forming part of a booth-frame 42, said turnstile controlling access to the voting front of the machine, Fig. 70. Tickets 43, bearing the names of the candidates and the offices for which they stand, are mounted on the front face of the partition-plate 15, and said tickets are provided with indices, such as Roman numerals, 75 corresponding with indices on the keys 20. Each of the tickets 43 is also inscribed with the word "Voted" immediately above the name of each candidate and in such position that said word is covered and concealed by 80 the key 20, provided for said candidate when said key is in normal position.

A locking device is provided for each row of single candidates and is constructed as follows: A plurality of plates 44 are mounted 85 for vertical reciprocation in bearings on the rear face of the partition 16 and engage each other end to end. Notches 45 are formed in the lower ends of the plates 44 to receive blades 46 on the arbors 21, and downward 90 movement of said plates is prevented by engagement with said blades. Upward movement of one, another, or all of the plates 44 is permitted to the extent of one-half of the width of either of the blades and no more, 95 further movement being prevented by engagement of the upper end of the upper plate with a stop or by engagement of another of the plates with a blade. The blades 46 project laterally equal distances from the centers of the arbors 21, and wings 47 are formed on and extend laterally from the outer end portions of said blades beyond the rear faces of the plates 44. When either of the keys 20 of a single-candidate row is 100 moved into voting position, either by voting a straight ticket or by voting a single key after scratching, the blade 46 on the moved key-arbor turns into the position shown by dotted lines in Fig. 4, with its width interposed between plates 44. Such turning of the blade lifts the plate or plates 44 above it to the limit of upward movement, and in its new position said blade prevents elevation of a plate 44 below it and prevents depression of the plates above it. By preventing depression of the plates above it the turned blade also prevents turning of another blade above it, and by locking the plate or plates below prevents turning of a blade in a lower 110 plane in the same candidate-row. Thus the turning of either single-candidate key into "voted" position effectually locks the remaining keys in the same candidate row. 115

A locking device is provided for each 120 group of plural candidates (where two or more candidate rows are grouped together in order that an elector may vote for more than one candidate) and is constructed as follows: A spring 48 is anchored at one end, in this in- 125

stance on a yoke 49, incapable of further downward movement, and then follows a sinuous course adjacent to blades 46^a on the arbors of two or more rows of keys 20, and is 5 adjustably anchored at its opposite end, in this instance by a screw 50 traversing a lug 51 on the plate 16. In this instance the blades 46^a are arranged at right angles to the positions of the blades 46 and normally occupy 10 planes parallel with the spring 48. There is sufficient slack between the ends of the spring 48 to permit just the desired number of keys to be turned, thus turning a plurality of blades 46^a (dotted lines, Fig. 5) and flexing the spring slightly from its true course. The spring is confined against lateral movement at points between the blades 46^a by bearings 52, fixed to the plate 16, and the flexing of said spring between said 15 bearings applies such tensile strain to the spring as to prevent turning of either of the other blades. Wings 47^a are formed on and extend laterally from and at right angles to the blades 46^a at the rear of the spring 48. Register 20 bearers or bars 53 are mounted for reciprocation in bearings 54, fixed to the rear face of the plate 16. The register bearers or bars 53 are parallel with and spaced apart from the plate 16, and one of such bars is provided 25 for each ticket. The register bearers or bars 53 are pivotally connected to the short arms of the pawls 35 by means of a rod 55, and since said pawls are rigid on the shaft 34, movable in one direction by the spring 38, yielding 30 pressure devices are thus provided to return the register-bearers at times. Vote-registers 56 (illustrated in conventional form in Fig. 2) are mounted on the register bearers or bars 53, and one of such registers is provided 35 for each of the candidates.

All of the mechanism necessary for voting straight tickets and making a choice from various mechanically-indicated tickets and preventing fraud relative thereto has now 40 been described, and the operation of voting therewith is as follows: The elector enters the booth as indicated by the arrow *a* in Fig. 10 and approaches the front of the machine. In advancing to the machine the elector moves 45 the turnstile 41 in the direction of the arrow *b* in Fig. 10. The movement of the turnstile 41 is communicated to and moves the crank-arm 39 forward, which results in a movement of oscillation of the shaft 34 in 50 one direction and causes the long arms of the pawls 35 to engage and move the straight-ticket bars 25 beyond the normal positions for voting, (shown in Fig. 1,) thus resetting the keys 20 in normal positions for voting, if 55 they have previously been voted. The elector then indicates his general choice of candidates by moving the straight-ticket key 17 of the party with which he affiliates downward through an arc, and by so doing he moves 60 the bar 25 of such party-ticket to the

right through engagement of an arm 19 with a stud 27. In the movement of the ticket-bar 25 to the right the lugs 28 29 on said bar engage arms 22 on arbors 21 and move all the keys 20 in one ticket row into 65 voted position, as shown in the first ticket-row in Fig. 1. Then the elector releases the key 17, which moves back under pressure of a spring 17^a, and the bar 25 is moved to the left into normal position for voting by the 70 link 31 engaging therewith and drawn by the spring 33, said spring being previously expanded by movement of the ticket-bar to the right in contact with the link. The elector may now leave the booth and in so doing 75 operate the vote-registers and counts the straight ticket he has indicated by moving the turnstile in a reverse direction, such reverse movement of the turnstile moving the rod 40 and crank-arm 39 rearward and 80 reversely oscillating the shaft 34. The reverse movement of the shaft 34 causes the long arms of the pawls 35 to engage and move the ticket-bars 25 to the extreme left and causes the short arms of the pawls to move the register 85 bearers or bars 53 to the right, whereby the vote-registers 56 are moved across the planes of and caused to engage with and be rotated by the wings 47 47^a on the blades 46 46^a. The reverse movement of the ticket- 90 bars 25 causes the lugs 29 thereon to engage arms 22 and reversely oscillate the keys 20 into normal position immediately following the engagement of the wings 47 47^a with and operation of the vote-registers 56. The reverse 95 movement of the turnstile 41 into the position shown in Fig. 10 locks the machine until a further initial movement of the turnstile under ordinary conditions. After indicating his choice of a straight ticket and before 100 leaving the booth and registering or counting the indicated vote the elector may cancel his entire ticket by reversely moving the keys 20, one at a time, to their initial positions, thereby removing the wings from the 105 range of possible contact with the vote-registers 56 on the further operation of leaving the booth. The elector may then indicate a choice on the same or a different ticket or tickets by moving one or more keys 20 downward through arcs into voted position, and he may so move any of the keys 20 not locked against movement by the plates 44 or spring 48 and forbidden to his selection. Thus is the elector permitted to select candidates to 110 the full allowance of the law or to cancel his vote and leave the booth assured that no other person has knowledge of his selection or choice.

We turn now to the consideration of means 115 employed for independent voting. Above the straight tickets there is a row of independent-ticket keys, one key 57 for each upright or candidate row of single-candidate offices and a key 57^a for each upright or candi- 120 125 130

date row of plural-candidate offices. A ballot-supply box 58 is located immediately above each of the keys 57, and a similar ballot-supply box 58^a is located immediately above each key 57^a. Each key 57 is formed with a notch 59 in its lower margin adapted to receive the beveled upper margin of an arm 60 on the upper end of the uppermost locking-plate 44 when said plate is raised by 10 the blade of a key voted below it. The notch 59 and arm 60 are correspondingly beveled to facilitate entrance of the arm to the notch and to insure the proper position of the key 57 at times. A yoke 61 is provided for each 15 key 57, and a similar yoke 61^a is provided for each key 57^a. The yokes 61 61^a are fixed to and extend horizontally rearward from the partition-plate 16 and embrace and extend around the rear ends of the keys 57 57^a. Retractile coil-springs 62 62^a connect the keys 57 57^a to the closed end portions of the yokes 61 61^a. Hooks 63 63^a are formed on and extend upward from the rear end portions of the keys 57 57^a and are adapted for travel 20 through slots in the bottoms of the ballot-supply boxes 58 58^a, a shoulder on the upper margin of each hook extending within the box. Ballots 64 are supplied to and rest on the bottoms of the boxes 58 58^a, and slots 65 25 are provided in the lower portions of the front wall of said boxes, through which the lowermost ballot may be removed by one or the other of the hooks. Springs 66 are fixed to the boxes 58 58^a and engage and depress the stacks of ballots 64 therein. The keys 57 30 are formed with ratchets 67 on their upper margins, and spring-detents 68, carried by the yokes 61, engage said ratchets and prevent premature return of the keys after they 35 have been drawn forward. Rock-shafts 69, mounted for oscillation in bearings fixed to the plate 16, are provided with slots to receive the spring-detents 68, and it is the function of said rock-shaft to lift said detents at 40 times and release the ratchets 67 in order that the keys 57 may be moved rearward by the springs 62. A rock-shaft 70 is mounted for oscillation in bearings fixed to the plate 16, and crank-arms 71 on said rock-shaft are 45 connected to crank-arms 72 on shafts 69 by rods 73. A crank-arm 74 on one end of the rock-shaft 70 is connected to a crank-arm 75 on the shaft 34 by a rod or link 76. Stops 77 77^a on the keys 57 57^a engage the yokes 61 61^a and limit and determine rearward movement of the keys under strain of the springs 62 62^a. The keys 57^a are provided with ratchets 67^a on their lower margins, and spring-detents 68^a, carried by the yokes 61^a, 50 engage said ratchets and prevent premature return of the keys after they have been drawn forward. Rock-shafts 69^a are provided and are formed with slots to receive the spring-detents 68^a. The rock-shafts 69^a are connected to the rock-shaft 70 in like manner as 55 the shafts 69 and have the function to depress the spring-detents at times and release the ratchets 67^a in order that the keys 57^a may be moved rearward by the springs 62^a. The keys 57^a are formed with notches 59^a in 70 their upper margins, which notches are adapted to receive yokes 49 at times to lock said keys against forward movement. The keys 57 57^a are locked against forward movement by the engagement of arms 60 or yokes 75 49 in the notches thereof only at such times that the plates 44 or springs 48 are performing their locking functions under the influence of other keys. When such locking functions are suspended (uninfluenced by 80 other keys) either of the independent keys may be drawn forward by an elector, and such forward movement of an independent key causes the hook thereon to deliver a ballot 85 64 to the elector, and said key is locked in its foremost position by its ratchet and detent. The elector may then mark the ballot given him and deposit it in a ballot-box 78 through a slot 79 (to be counted later by the officers of election) or he may destroy or 90 carry it away; but he cannot cancel such independent ballot and vote a mechanical choice in lieu thereof. It is designed that an elector shall cancel a mechanically-indicated selection of candidate before he exercises a selection by independent ballot, and he may make as many cancellations and substitutions of ballots as there are candidates to be voted for by him. The operation of leaving the booth and registering or counting the mechanically-indicated vote above described 95 repositions all the independent keys that have been used by the departing elector through an oscillation of the rock-shaft 70 by the rock-shaft 34, crank-arm 75, link 76, and 100 crank-arm 74, whereby the ratchets on said independent keys are released and the keys are drawn back by the springs 62 62^a. It will be observed that yokes 49 on the independent keys 57^a are grouped on the spring 105 48 and as many yokes are provided on a given locking-spring as there are offices in such group.

A series or row of keys 80 81 is arranged below the candidate rows of keys and are set 110 in pairs, one pair for each "question" to be submitted to the electors. The keys 80 81 are of a construction identical with the keys 20, and locking-plates 44^a are arranged between them, one plate for each pair of keys. 115 A bar 25^a is mounted for rectilinear reciprocation beneath the row of keys 80 81 and is provided with studs 29^a, adapted to return the keys to normal position when a vote is recorded. The bar 25^a is acted upon by a 120 pawl 35 on the shaft 34, but does not have a returning link, since it is not moved to vote a question and is moved only to the left from 125 normal position to reset the used question-keys. A register bearer or bar 53^a is pro- 130

vided for the row of question-keys and is equipped with vote-registers 56^a. The register bearer or bar 53^a is attached to the shaft 34 and is operated thereby in the manner described above in connection with the bars 53 to register or count the vote on questions. The use of either key 80 81 to indicate a vote on a question locks the other key of the pair as to such question through the use of the locking-plate 44^a.

In some localities and on some occasions all the electors are not qualified to vote on all candidates or questions, and I have made provision for locking all questions and candidates as to which an elector is disqualified, as follows: A plurality of bell-crank levers 82 83 are provided and are fulcrumed on the plate 16. Each of the levers 82 83 is formed with a long arm extending across the path of travel of removable and replaceable studs 84 in a locking-bar 85, mounted for rectilinear reciprocation on the plate 16. Each of the levers 82 is formed with a short arm adapted to engage the lower end of the lowermost plate 44 of a vertical row of such plates and lift them into such position that neither of the candidate-keys or independent keys of such row may be moved to voted position. Each of the levers 83 is formed with a short arm engaging and controlling a block 86, whereby strain may be applied to exhaust the slack of a locking-spring 48 and prevent the movement of any group key controlled by said spring into voted position. A plurality of levers 87 of the second class are fulcrumed at their lower ends on the plate 16 and extend upward across the horizontal plane of the row of question-keys 80 81 and have their upper end portions crossing the path of travel of studs 88, removably and replaceably mounted in the locking-bar 85. A rock-shaft 89 is mounted for oscillation parallel with the shaft 34 in bearings fixed to the plate 16 and is connected by a crank-arm 90 thereon to one end of the locking-bar 85. A retractile coil spring 91 connects one end of the locking-bar 85 to the plate 16. A crank-arm 92 on one end of the rock-shaft 89 is connected by a rod 93 to a turnstile 94 in and forming part of a booth-frame 42. The machine is adjusted before voting is commenced for the use of all classes of electors by removing the studs 84 or 88 in respect of those offices for which all classes of electors may exercise the franchise. Then those electors who are disqualified as to some of the offices or questions are admitted through the turnstile 94 and are permitted to depart the same way. On entering by way of the turnstile 94 an elector actuates the locking-bar toward the right through the rod 93, arm 92, shaft 89, and arm 90, and such movement of the locking-bar causes the remaining studs 84 and 88 to engage levers 82, 83, and 87 and put said levers in such positions as will lock

the plates 44, springs 48, and plates 44 against such candidates and questions as come within the disqualification. The elector then approaches the voting-face of the machine through the turnstile 41, makes his selection with the keys remaining unlocked, departs through the turnstiles, and in so doing registers or counts his selection and resets the machine for the next elector. On return of the turnstile 94 to normal position 75 the spring 91 returns the locking-bar 85 to normal position and releases the levers 82, 83, and 87 from the influence of the studs 84 and 88.

I claim as my invention—

1. In a voting-machine, a party row of keys, each key formed with an arm, a bar mounted for reciprocation, studs on said bar adapted to engage said arms simultaneously, means for registering a vote, register-actuating devices adapted to be operatively positioned by said keys, and means for retuning said keys to normal position, which means comprises springs for returning said bar and a stud on said bar, which with the first-mentioned studs, engage the arms of the keys in a reversing direction.

2. In a voting-machine, a party row of keys, each key formed with an arm, a bar mounted for manual reciprocation in one direction and spring-actuated in the opposite direction, studs on said bar adapted to engage said arms simultaneously and move said party rows of keys in one direction, resetting devices on said bar adapted to move said party row of keys to unvoted or normal positions, vote-registering devices, register-actuating wings normally inoperative and mounted on said keys and adapted to be moved thereby through arcs to operative positions, mechanism adapted to move said vote-registering devices simultaneously to registering positions in contact with said register-actuating devices, and means for moving said mechanism to initial position.

3. In a voting-machine, a party row of keys, a bar mounted for manual reciprocation in one direction and spring-actuated in the opposite direction, connections between said bar and keys to move said keys simultaneously, register-actuating wings mounted on and adapted to be moved through arcs into operative positions by said keys, a register-bearer mounted for reciprocation parallel with said bar, registers on said register-bearer and adapted for contact with and progression by said register-actuating devices in the movement of said register-bearer in one direction, means adapted for manual actuation for moving said register-bearer in one direction, and yielding pressure devices for moving said register-bearer in the opposite direction.

4. In a voting-machine, a series of candidate-keys mounted for oscillation, a bar

5 mounted for reciprocation and common to and adapted for engagement with all of said keys, arms on said keys, lugs on said bar adapted to be engaged by said arms to move said bar in one direction, another lug on said bar adapted to coöperate with the first lugs in returning said keys, said candidate-keys formed with wings adapted to be turned with said keys into operative positions, a register-bearer mounted for reciprocation parallel with said bar, registers mounted for revolution on said bearer, one register for each candidate-key, means for moving said bearer, a straight-ticket key adapted to engage and move said bar in one direction and a spring adapted to move said bar in the opposite direction.

6. In a voting-machine, a series of keys mounted for oscillation, a plate carrying said keys, springs between said keys and plate and tending to hold said keys stationary, a bar mounted for reciprocation and common to and adapted for engagement with all of said keys, arms on said keys, lugs on said bar adapted to be engaged by said arms to move said keys in one direction, another lug on said bar adapted to coöperate with the first lugs in returning said keys, said keys formed with wings adapted to be turned with said keys into operative positions, a register-bearer mounted for reciprocation parallel with said bar, registers mounted for revolution on said bearer, one register for each key, means for moving said bearer, a straight-ticket key adapted to engage and move said bar in one direction, and a spring adapted to move said bar in the opposite direction.

7. In a voting-machine, a plate, a series of keys mounted for oscillation in said plate, springs between and impinging said plate and keys and tending to hold said keys stationary, a bar mounted for rectilinear reciprocation on said plate, said bar common to and adapted for engagement with all of said keys, arms on said keys, lugs on said bar adapted to be engaged by said arm to move said keys in one direction, another lug on said bar adapted to coöperate with the first lugs in returning said keys, a straight-ticket key adapted to engage and move said bar in one direction and a spring adapted to move said bar in the opposite direction.

8. In a voting-machine, a bar mounted for reciprocation, a stud on said bar, a shaft mounted for oscillation and formed with an arm adapted to engage said stud, a straight-ticket key on said shaft and adapted for manual actuation, and a spring for returning said key to initial position independent of said bar.

9. In a voting-machine, a bar mounted for reciprocation, a shaft mounted for rotation, an arm on said shaft, a candidate-key on said shaft, a friction-spring on said shaft, a stud on said bar adapted to engage said

arm, and rotate said shaft in one direction, and another stud on said bar adapted to engage the opposite side of said arm in a reverse movement of said bar and return said shaft.

10. In a voting-machine, a bar mounted for reciprocation, plates mounted for reciprocation transversely of said bar, a shaft mounted for oscillation, a candidate-key on said shaft, an arm on said shaft, a stud on said bar adapted to engage said arm, and rotate said shaft in one direction, and another stud on said bar adapted to engage the opposite side of said arm in a reverse movement of said bar and return said shaft, and a blade on said shaft adapted to engage one or another of said plates.

11. In a voting-machine, a bar mounted for reciprocation, a shaft mounted for oscillation, a washer on said shaft, a spring on said shaft, a candidate-key on said shaft, and studs on said bar adapted to engage said arm.

12. In a voting-machine, a bar mounted for reciprocation, locking devices, a shaft mounted for oscillation, an arm on said shaft, a stud on said bar adapted to engage said arm, and rotate said shaft in one direction, and another stud on said bar adapted to engage the opposite side of said arm in a reverse movement of said bar and return said shaft, a blade on said shaft, adapted to engage one or another of said locking devices, a register-bearer, vote-registers on said register-bearer, a wing on said blade, and means for moving said register-bearer to bring a vote-register into contact with a wing.

13. In a voting-machine, a series of candidate-keys mounted in a row and each arranged for manual oscillation, arms on said keys, a bar mounted for longitudinal movement adjacent said keys, studs on said bar adapted to engage said arms and move said keys conjunctively, said studs and another stud on said bar acting as resetting devices in a reverse movement of the bar, a straight-ticket key mounted for manual actuation and having an arm, a stud on said bar adapted to be engaged by the arm on the straight-ticket key, a spring-drawn link adapted to engage and return said bar after manual movement thereof, wings on said candidate-keys, and registering devices adapted to engage said wings.

14. In a voting-machine, ticket rows of keys, ticket-bars adapted to engage and move said keys in rows, straight-ticket keys adapted for manual actuation to move said ticket-bars, yielding-pressure devices adapted to act on and return said ticket-bars, and studs on said ticket-bars alternately acting upon and acted upon by said keys.

Signed by me at Des Moines, Iowa.

FREDERIC S. THORNLEY.
